UNITED STATES PATENT OFFICE.

AUGUST LINDGREN, OF MOLINE, ILLINOIS, ASSIGNOR TO THE MOLINE PLOW COMPANY, OF ILLINOIS.

PLOWSHARE.

SPECIFICATION forming part of Letters Patent No. 623,726, dated April 25, 1899.

Application filed January 31, 1899. Serial No. 704,005. (No model.)

To all whom it may concern:

Be it known that I, AUGUST LINDGREN, of Moline, county of Rock Island, and State of Illinois, have invented a new and useful Improvement in Plowshares, of which the following is a specification.

Cast-iron plowshares such as now extensively used are attended with a very serious objection—namely, their extreme liability to breakage due to the natural brittleness of the cast-iron, it frequently occurring that such shares are broken during the operation of attaching them to the plow. It is the aim of my invention to obviate this objectionable feature and to so strengthen shares of this character that the liability of their being broken is reduced to a minimum, or in the event of a breakage occurring the strengthening means will serve to hold the fractured parts securely together in their normal relative positions, admitting of the unimpaired use of the share, whereby it may, even though its cast-metal portion be broken, be effectively used and efficiently perform its functions until worn out.

To these ends my invention consists in providing the share with a tough-metal strengthening member, preferably in the form of a steel or wrought-metal strap embedded in the metal share during the casting operation.

The invention further consists in the details more fully hereinafter described.

In the accompanying drawings, Figure 1 is an inside elevation of a cast-iron plowshare, showing my preferred form of strengthening member applied thereto. Fig. 2 is a cross-section of the same on the line 2 2 of Fig. 1.

Referring to the drawings, A represents a cast-iron plowshare of customary form, and B a strengthening member in the form of a strip or strap of some stronger tougher metal—such, for instance, as steel or wrought-iron. This strengthening member is applied to the share at or near its longitudinal center and is embedded directly into the cast-iron composing the share during the operation of casting the same, whereby it will be held firmly and securely in place by the cast metal flowing around and partially overlying its edges, as illustrated at C C.

I propose as the simplest and least expen-

sive manner of producing the above-described share complete, with the strengthening member applied thereto, to place the strap of steel or wrought-iron into the mold in the desired 55 position and then fill the mold with the molten iron which is to form the share proper, whereby the share on leaving the mold will have the strengthening member firmly embedded therein, as above described; but while 60 I propose this as the simplest manner of applying the strengthening member it is to be understood that I do not limit or confine myself to this mode, as the same may be applied in any convenient manner which admits of 65 the accomplishment of the ends in view without departing from the scope of my invention, the essence of which resides in providing a plowshare with a strengthening member of tougher metal which will serve the 70 functions of decreasing the liability of the share being broken and which will in the event of such an accident occurring hold the fractured parts securely together in their normal positions, thus admitting of the unim- 75 paired use of the share. Further, while I have described the strengthening member as located at the longitudinal center of the share and while I prefer to so situate it, as in this position its strengthening qualities are 80 more universal and in the event of a breakage of the share occurring it serves to more firmly hold the parts together, it will be understood that it may be located in any de- 85 sired position which will not detract from its efficiency of operation without departing from the spirit of my invention. So, also, the form of said strengthening member and the metal composing it may be variously modi- 90 fied in like manner.

It will be seen that by the application to a cast-iron share of a tougher-metal strengthening member I produce a share possessing such durability and strength for all practical purposes as would be obtained in an entire 95 steel or wrought-iron share and this without materially increasing the cost over that of the ordinary cast-iron share.

Having thus described my invention, what I claim is—

1. The combination with a plowshare of a tough-metal strengthening member applied

thereto distant from its edge, substantially as described.

2. The combination with a plowshare of a tough-metal strengthening member embedded therein distant from its edge, substantially as described.

3. The combination with a plowshare of a tough-metal strengthening member applied thereto at or near its longitudinal center, substantially as described.

4. The combination with a cast-iron plowshare of a tough-metal strengthening member cast directly therein at or near its longitudinal center, substantially as described.

5. The combination with a cast-iron plow-share of a longitudinally-extending tough-metal strengthening-strip embedded therein with the material of the share overlapping the edges of the strip; whereby said strip is held firmly and securely in place, substantially as described. 15 20

In testimony whereof I hereunto set my hand, this 18th day of January, 1899, in the presence of two attesting witnesses.

AUGUST LINDGREN.
